PORTABLE OUTDOOR GRILL

Otho Jennings, Coushatta, La.

Filed July 26, 1963, Ser. No. 75,987

Term of patent 14 years

(Cl. D81—10)

FIGURE 1 is a top plan view of a portable outdoor grill embodying the new design;

FIGURE 2 is a lateral cross-section through the portable outdoor grill of FIGURE 1;

FIGURE 3 is a view from beneath the portable outdoor grill of FIGURE 1; and

FIGURE 4 is a front elevational view of the portable outdoor grill shown in FIGURE 1.

The essential features of the design are shown in solid lines in the drawing.

I claim:

The ornamental design for a portable outdoor grill, substantially as shown and described.
